FRED LICHTENBERG AND MICHAEL M. McCARTHY, OF YONKERS, NEW YORK.

METHOD OF BUILDING CONSTRUCTION.

1,348,018.

Specification of Letters Patent. Patented July 27, 1920.

Application filed October 13, 1919. Serial No. 330,161.

To all whom it may concern:

Be it known that we, FRED LICHTENBERG and MICHAEL M. McCARTHY, citizens of the United States, residing at Yonkers, in the 5 county of Westchester and State of New York, have invented certain new and useful Improvements in Methods of Building Construction, of which the following is a specification.

- 10 This invention has relation to a method of building construction and has for an object to provide a method of construction which consists in employing sections or slabs of material composed of reinforced plastic 15 material of such a nature that the sections may be secured to studding or the like merely by driving nails or other suitable fasteners through the material into the studding.
- 20 Another object of the invention is to provide a method of building construction of the character above set forth which consists in employing slabs of reinforced plastic material, the reinforcement projecting beyond 25 the edges of the slab whereby the slabs may be so arranged as to cause the projecting reinforcing element to lie in overlapped or staggered relation whereby plastic material may be subsequently inserted in the spaces 30 between the slabs and by binding the reinforcing elements of the adjacent slabs together form a perfect bond.

In addition to the foregoing, this invention comprehends improvements in the 35 details of construction and arrangement of parts, to be hereinafter described and particularly set forth in the appended claims.

In the accompanying drawings in which similar and corresponding parts are designated by the same characters of reference throughout the several views in which they appear,

Figure 1 is a view in side elevation illustrating our method of building construction.

45 Fig. 2 is a detail view on an enlarged scale illustrating the manner in which the bond is formed, and

Fig. 3 is a sectional view taken on the line 3-3 of the preceding figure.

50 With reference to the drawings, 10 indicates a slab, the same being preferably oblong in configuration and consisting of a material which is plastic when wet and hard when dry. The composition of the material 55 may be cement with sand, gravel or any other suitable filling agent and the composi-

tion does not form a part of the present invention. Extending throughout the mass of the slab is a reinforcement of wire fabric which may be relatively coarse, and consisting of the vertical strands 11 and the horizontal strands 12. The vertical strands are arranged in pairs and formed with loops 13 at their ends, while the strands 12 are separate and independent and project beyond 60 the vertical ends of the slab as shown in Fig. 2. Applied to the rear face of the slab 10 is a layer of hard paper 14 or the like, the edges of the paper extending beyond 65 the edges of the slab as shown at 15.

In use, the slabs are applied to the studs 16 by means of nails 17, the latter being driven right through the material of the slabs, and into the studs, the nature of the material employed in forming the slabs being such as to stand the insertion of the penetrative elements without breaking or cracking. The slabs are arranged in such a manner as to break the joints as shown in Fig. 1 and where adjacent ends of slabs 80 are applied to a stud, nails are driven through the ends of both slabs into the same stud. It will be noted that the slabs are in spaced relation owing to the projecting ends of the reinforcing elements 11 and 12 85 and it also will be noted that the slabs are arranged relatively so that the loops 13 at the upper and lower edges of the slab will be in relatively overlapped or staggered relation. It will also be noted that 90 at the vertical edges of the slabs the projecting ends of the horizontal element 12 are likewise arranged in overlapped or staggered relation. The spaces between the slabs are then filled by means of a suitable binding agent such as mortar as indicated at 18. It will be noted that the projecting edges 95 of the hard paper section 14 are disposed in overlapping relation thus covering the joints between the slabs, and forming on the front side a base upon which the mortar joint 18 may be applied. It will be obvious that if the inner surface of the slabs is to be plastered that the tar paper will form a base upon which the plaster may be applied. Thus it will be seen that we have provided a novel method of building construction in which the material employed is easily transportable, and which may be cheaply and quickly constructed, and which 110 is at the same time durable and easily applied. It will be apparent that the pro-

vision of the tar paper renders the material air tight and damp proof, the overlapping edges of the paper protecting the joint between the slabs. The relation of the reinforcing elements in the manner in which they are projected beyond the edges of the slabs enables the perfect bond to be formed between the slabs making the wall practically a monolithic construction. Other uses and advantages will readily occur to those skilled in the art to which this invention appertains.

While we have illustrated and described our invention with some degree of particularity we realize that in practice various alterations therein may be made. We therefore reserve the right and privilege of changing the form of the details of construction or otherwise altering the arrangement of the correlated parts without departing from the spirit of the invention or the scope of the appended claim.

Having thus described our invention, what we claim as new and desire to secure by 25 United States Letters Patent is:

A wall construction comprising vertical spaced studding, a plurality of slabs of planed material nailed to said studding in broken joint formation with the edges of the slabs in

spaced relation, each slab having a reinforcing element molded therein in a form of a sheet of woven wire fabric the edges of which extend beyond the edges of the slab, the vertical strands of said reinforcing element being looped at each end, a horizontal strand straight with each end said loop being arranged between the loop of reinforcing element of adjacent slab and the projecting edges of the horizontal strands being arranged in overlapping relation with respect to the projecting edges of the reinforcing element of adjacent slabs, a covering of tar paper upon the rear face of each slab said paper projecting beyond the edges of each slab to a distance corresponding to the extent of projection of the reinforcing element thereof whereby said paper edges of adjacent slabs may be overlapped, and a bond of plastered material filled in between the slabs.

In testimony whereof we affix our signatures in presence of two witnesses.
